WELL PERFORATOR

William Bendeler and Clifford Howard,
Oklahoma City, Okla.

Application April 11, 1940, Serial No. 329,182

13 Claims. (Cl. 164—0.3)

This invention relates to improvements in casing perforators, and more particularly, but not by way of limitation, to a casing perforator for an oil well hole or the like.

In oil wells it is often desirable to perforate the well casing at various elevations for tapping different oil bearing stratas and restoring the well to production. Furthermore, casing perforators are utilized for determining a faulty cementing job in a well, to re-establish circulation in frozen strings of casing by providing channels through the casing, and providing channels in the well casing and cement preparatory to acid treatment of a well. Heretofore, casing perforators such as those disclosed in the prior patents to Hardison, No. 650,318, Wood, No. 1,779,652 and Schull, No. 1,853,239, the perforating tool usually comprises a set of bowed or "belly" springs which have a tendency to drag against the inner periphery of the well casing during lowering or removing operation of the perforator. In cases of crooked well holes, the well casing is out of alignment and perforators of this type can not be utilized because the drag of the bowed springs will cause a jamming or "freeze" and prevent lowering of the perforator into the well hole.

It is therefore an important object of this invention to provide a casing perforator capable of being easily lowered or removed from a well hole, or capable of insertion in smaller or disaligned well casings due to elimination of any drag of the perforator elements against the casing.

A further object of this invention is to provide a casing perforator having rotatable knife actuating means engaging the casing to cause rotation thereof, said means capable of contacting the casing at all times without any slippage.

An additional object of this invention is to provide a casing perforator capable of providing a more efficient and positive actuation of a pivotable knife by providing an efficient and rolling contact between the knife and the actuating means, said means being a knurled wheel to prevent slippage.

A further object of this invention is to provide a casing perforator in which the cutting knife can be released more efficiently because the actuating means for the knife is immediately moved out of the path of the knife upon a knocking loose or release action.

And still a further object of this invention is to provide a casing perforator having a floating collar adapted to actuate a trip assembly allow-

ing positive setting of the casing perforator in the well hole.

Other objects and advantages of the invention will be evident from the following detailed description read in conjunction with the accompanying drawings which illustrate one form of my invention.

Fig. 1 is a sectional view in vertical elevation of the perforating tool shown disposed in the well casing.

Fig. 2 is a similar view showing the actuation of the knife for fracturing the casing.

Fig. 3 is a similar view showing full perforation of the well casing by the perforating tool.

Fig. 4 is an elevational view showing the jarring tools connected to the perforator body.

Fig. 5 is a view taken on lines 5—5 of Fig. 2.

Fig. 6 is a view taken on lines 6—6 of Fig. 3.

The perforator provided in this invention is capable of cutting or punching outwardly in comparatively great distances, and is useful in situations where it is desired to perforate two strings of pipe or where the pipe or casing is cemented by a body of cement or the like, and it is desired to perforate the cement as well as the casing.

Referring to the drawings in detail, and more particularly to Figs. 1, 2 and 4, the casing perforator herein illustrated is adapted to be lowered into the well casing 2 on a cable or wire 30 line 4 secured at the top of the well to a reciprocating walking beam or any similar apparatus capable of producing a quick braking action or stop action (not shown). The lower end of the cable 4 is connected to a straight bar or stem 6 providing weight, and adapted to receive a threaded socket 8 securing the cable. The lower end of the bar 6 is secured to a jar 10, which in turn is threaded to an upper neck portion 11 of the perforator. It will be apparent that the jarring tools can be of any conventional type to provide a jarring action for assisting the cable in setting or releasing the perforator tool in the well casing 2.

The casing perforator comprises a cylindrical body portion 12 having a recess 14. The recess is disposed longitudinally of the body 12 and extends inwardly from one side of the body to a point approaching the opposite side of the body. In practice, the recess may be milled or otherwise formed in the solid body 12. The upper portion of the recess 14 is formed with a smaller recess 16 in which is anchored a stud or pin 18. A perforating knife 20 is pivoted on the pin 18 for a purpose as will be hereinafter set forth. 55

Referring to Fig. 5 it is to be noted that the walls of the recess 14 are milled out or cut away to form a pair of diametrically opposed grooves or cam slots 22 and 24. As is clearly apparent from Figs. 1 to 3, the grooves are of an irregular axial contour for a purpose as will be hereinafter set forth. The inner face of recess 14 is provided with a cut away portion 26 for receiving a cam member 28 secured to the housing 10 or body 12 by bolts 30. A wheel 32 is disposed in the recess 14 and is journalled on a stud or shaft 34 having its opposite ends disposed in the grooves 22 and 24 for guiding the floating wheel complementary to the contour of the grooves. The wheel comprises a central body portion 36 having a pair of oppositely disposed knurled projections or flanges 38.

The lower portion of the housing 12 is provided with an aperture 40 through which extends a shaft 42. The extreme lower end of the housing is provided with threads 44 for receiving an apertured cage 46 in which is encased a helical spring 48. The shaft extends from the aperture 40 through and below the apertured cage 46, it being understood that the spring 48 surrounds the shaft 42. The shaft is provided with an annular flange 50, which in one position of the shaft compresses spring 48 (see Fig. 1). The upper end of the shaft is threaded to receive a nut 52 limiting the downward movement of the shaft 42, as well as forming a support for the body portion 36 of the wheel 32 when in an inoperative position. The lower portion of the shaft 42 is cut away to form recesses 54 in which is anchored a pin 56. A latch member 58 is pivotably secured to the pin 56. A small helical spring 60 is disposed between the latch member and the inner face of the recess 54 for urging the latch 58 into an inoperative position. The latch member is provided with a shoulder portion 62, which in operative position abuts against the lower face of cage 46 for restraining upward axial movement of the shaft 42. It will be apparent from this construction that any possibility of drag by the perforator is eliminated during the lowering or removal operation.

A floating or loosely mounted collar 64 is disposed on the lower end of the shaft 42, and is held thereon by a nut 66 secured to the shaft.

50 Operation

In operation the perforator is set as shown in Fig. 1, and lowered into the well hole to any desired elevation in order to perforate the casing. Reciprocation of the cable will cause a reciprocal thrust of the jarring tools with a complementary reciprocation of the housing 12 whereupon the floating collar 64 is moved axially upward to contact the abutting portion of the latch and disconnect the latch 58 from its abutting position with the lower face of the cage 46. With the latch in inoperative position, the tension spring 48 through the medium of flange 50 moves the shaft 42 rapidly upward with a simultaneous upward movement of the knurled wheel 32. During the lowering of the perforator, the wheel is supported by the nut 52, and due to the contour of cam like grooves 22 and 24, the wheel is positioned out of contact with the inner periphery of the casing 2. With upward movement of the shaft 42 and knurled wheel 32, the contour of the central portion of grooves 22 and 24 positions the knurled flanges 38 into biting engagement with the inner periphery of the casing 2 for setting the perforator in the hole. It will be apparent

that one face of the cam 28 is substantially complementary to the contour of the grooves 22 and 24 to assist the positioning of the wheel 32. Continued reciprocating thrusts of the jarring tools forces the perforator housing 12 downwardly with a simultaneous rotation of the wheel due to the engagement with casing 2, whereupon the knife 20 is moved downward into contact with the portion 36 of the wheel and is swung into cutting position as clearly shown in Fig. 2. In this position the knife is bearing against the casing 2, and a continued jarring action causes the knife to pivot about the pin 18 and perforate an axial slot in the casing, cement or the like. The downward jarring action to move the knife 20 through the casing simultaneously moves the wheel 32 into the position shown in Fig. 3 out of contact with the casing.

The disposition of the pin 18 in the small recess 16 allows all downward thrusts or jarring action 20 to be received by the housing 12 rather than the pin 18. During perforation of the casing by the knife 20 the wheel is positioned out of biting engagement with the casing 2, as shown in Fig. 3. Release of the knife 20 is affected by an upward 25 pull of cable 4 which again brings the wheel 32 into contact with the casing 2. Continued jarring action in moving the body 12 upward, simultaneously rotates the wheel whereas the wheel is positioned out of contact with the casing in 30 accordance with the contour of the lower portion of grooves 22 and 24. The wheel in this position abuts the nut 52 and overcomes the tension of spring 48 slightly to allow the out of contact 35 positioning of the wheel. However, the spring 48 is of sufficient strength to prevent re-setting of the latch 58. Also the spring 60 assists in holding the latch in inoperative position. The latch 58 can not be re-set without pulling the perforator from the well hole, and it will be apparent from the above description that the perforator can not be utilized for perforating the casing at a point lower than the original setting 40 position without re-setting the latch. However, the perforator can be utilized for cutting the 45 casing as often as it is desired at elevations above the original setting position without pulling the perforator from the hole. When it is desired to again perforate the casing, the operation previously described is repeated.

From the foregoing it will be apparent that this invention provides a casing perforator which is simple in construction, wherein the perforator can be easily lowered into well holes having small or disaligned casings due to the utilization of the 55 trip assembly preventing any drag of the perforator in the lowering operation. Furthermore, the knurled wheel for actuating the knife provides a positive and rolling contact to assure an efficient pivoting of the knife for perforating the 60 casing.

Changes may be made in the combination and arrangement of parts as heretofore set forth in the specification and shown in the drawings, it being understood that any modification in the 65 precise embodiment of the invention may be made within the scope of the following claims without departing from the spirit of the invention.

What we claim is:

1. In a perforator adapted to be lowered into 70 a well casing comprising a longitudinally recessed body portion, a knife pivotably mounted in the recess, cam grooves formed in the recess, said grooves comprising inclined end portions and a vertical central portion, a wheel mounted on a 75

shaft disposed in the grooves, means carried by the body portion for moving the wheel from the lower inclined portion to the vertical portion whereby said wheel is positioned in biting engagement with the inner periphery of the casing for actuating the knife.

2. In a perforator adapted to be lowered into a well casing comprising a longitudinally recessed body portion, a knife pivotably mounted in the 10 recess, cam grooves formed in the recess, said grooves comprising inclined end portions and a vertical central portion, a wheel mounted on a shaft disposed in the grooves, means carried by the body portion for moving the wheel from the lower inclined portion to the vertical portion 15 whereby said wheel is positioned in biting engagement with the inner periphery of the casing for actuating the knife, and cam means disposed in the recess and cooperating with the grooves for 20 positioning the wheel.

3. In a perforator adapted to be lowered into a well casing comprising a longitudinally recessed body portion, a knife pivotably mounted in the recess, cam grooves formed in the recess, said 25 grooves comprising inclined end portions and a central vertical portion, a knurled wheel mounted on a shaft disposed in the grooves, means carried by the body portion for moving the wheel from a lower inclined portion to the vertical portion 30 whereby said wheel is positioned in biting engagement with the inner periphery of the casing for setting the perforator, said wheel in set position adapted to be rotated into contact with the knife upon a downward movement of the body 35 portion.

4. In a perforator adapted to be lowered into a well casing comprising a longitudinally recessed body portion, a knife pivotably mounted in the recess, cam grooves formed in the recess, said 40 grooves comprising inclined end portions and a central vertical portion, a knurled wheel mounted on a shaft disposed in the grooves, means carried by the body portion for moving the wheel from a lower inclined portion to the vertical portion 45 whereby said wheel is positioned in biting engagement with the inner periphery of the casing for setting the perforator, said wheel in set position adapted to be rotated into contact with the knife upon a downward movement of the body 50 portion, and cam means disposed in the recess and cooperating with the grooves for positioning the wheel.

5. In a perforator adapted to be lowered into a well casing comprising a body portion having a 55 longitudinal recess, a knife pivotably mounted in the recess, cam grooves formed in the recess, a knife actuating wheel mounted on a floating stud disposed in the cam grooves, means slidably mounted on the body portion for moving the 60 wheel into biting engagement with the inner periphery of the casing, said wheel rotatable along the grooves in response to a downward movement of the body portion for moving the knife into contact with the casing.

6. In a perforator adapted to be lowered into a well casing comprising a body portion having a longitudinal recess, a knife pivotably mounted in the recess, cam grooves formed in the recess, a knife actuating wheel mounted on a floating 70 stud disposed in the cam grooves, means slidably mounted on the body portion for moving the wheel into biting engagement with the inner periphery of the casing, said wheel rotatable along the grooves in response to a downward movement of the body portion for moving the 75

knife into contact with the casing, said grooves formed with an upper inclined portion for positioning the wheel out of contact with the casing during the perforation thereof.

7. In combination with a perforator adapted to be lowered in a well hole, a longitudinally recessed body portion, jarring tools disposed above the body portion, a cutter pivotably mounted in an upper portion of the recess, cam grooves formed in the recess, a knurled wheel mounted on the movable stud disposed in the grooves, means responsive to a jarring action of the tools for moving the wheel along the cam grooves into biting engagement with the inner periphery of the casing, said wheel in biting engagement adapted to 15 be rotated along the grooves in response to a jarring action providing downward movement of the body portion for moving the cutter into engagement with the casing.

8. In combination with a perforator adapted to be lowered in a well hole, a longitudinally recessed body portion, jarring tools disposed above the body portion, a cutter pivotably mounted in an upper portion of the recess, cam grooves formed in the recess, a knurled wheel mounted on the movable stud disposed in the grooves, means responsive to a jarring action of the tools for moving the wheel along the cam grooves into biting engagement with the inner periphery of the casing, said wheel in biting engagement adapted to 20 be rotated along the grooves in response to a jarring action providing downward movement of the body portion for moving the cutter into engagement with the casing, and a cam body disposed in the recess and cooperating with the 25 grooves for positioning the wheel.

9. In a perforator adapted to be lowered in a well casing comprising a longitudinally recessed body portion, a cutter pivotably mounted in the recess, cam grooves formed in the recess below the 40 cutter, a cutter actuating wheel mounted on a stud slidably disposed in the cam grooves, a slidable shaft mounted in the body portion for moving the wheel along the cam grooves into biting engagement with the inner periphery of the casing, 45 pivotable latch means restraining movement of the slidable shaft during lowering of the perforator in the casing, a floating collar disposed on the shaft for releasing the latch means, and spring means for moving the shaft rapidly upward 50 upon release of the latch means.

10. In a perforator adapted to be lowered into a well casing comprising a longitudinally recessed body portion, a cutter pivotably mounted in the recess, cam grooves formed in the recess below the 55 cutter, a cutter actuating wheel mounted on a stud slidably disposed in the cam grooves, means slidably mounted in the body portion for moving the wheel along the cam grooves into biting engagement with the inner periphery of the casing, means restraining movement of the slidable means during lowering of the perforator, floating means disposed on the slidable means for releasing the restraining means, and means for moving the slidable means rapidly upward upon 60 release thereof.

11. In combination with a perforator adapted to be lowered into a well casing, a cylindrical body portion having a longitudinal recess, jarring tools disposed above the body portion, a cutter 70 pivotably mounted in the recess, cam grooves formed in the recess below the cutter, a cutter actuating wheel mounted on a stud slidably disposed in the cam grooves, knurled flanges provided on the wheel, a slidable shaft mounted in 75

the body portion for moving the flanges of the wheel into biting engagement with the casing, a pivotable latch carried by the shaft and adapted to contact the lower portion of the body for restraining movement of the slideable shaft during lowering of the perforator, a floating collar disposed on the shaft and responsive to a jarring action releasing the latch, and spring means for moving the shaft rapidly upward upon release thereof.

12. In combination with a perforator adapted to be lowered in a well casing, a cylindrical body portion having a longitudinal recess, jarring tools disposed above the body portion, a cutter pivotably mounted in the recess, grooves formed in the recess below the cutter, said grooves comprising inclined end portions and a vertical central portion, a cam provided in the recess and having one face complementary with the contour of the grooves, a cutter actuating wheel mounted on a stud slidably disposed in the grooves, knurled flanges provided on the wheel, a slideable shaft mounted in the body portion for moving the flanges of the wheel into biting engagement with the casing, a pivotable latch carried by the shaft and adapted to contact the lower portion of the body for restraining movement of the shaft during lowering of the perforator, a floating collar disposed on the shaft and responsive to a jarring action for releasing the latch, spring means for moving the shaft rapidly upward upon release of the latch whereby said wheel is moved along the

grooves into biting engagement with the inner periphery of the casing.

13. In combination with a perforator adapted to be lowered in a well casing, a cylindrical body portion having a longitudinal recess, jarring tools disposed above the body portion, a cutter pivotably mounted in the recess, grooves formed in the recess below the cutter, said grooves comprising inclined end portions and a vertical central portion, a cam provided in the recess and having one face complementary with the contour of the grooves, a cutter actuating wheel mounted on a stud slidably disposed in the grooves, knurled flanges provided on the wheel, a slideable shaft mounted in the body portion for moving the flanges of the wheel into biting engagement with the casing, a pivotable latch carried by the shaft and adapted to contact the lower portion of the body for restraining movement of the shaft during lowering of the perforator, a floating collar disposed on the shaft and responsive to a jarring action for releasing the latch, spring means for moving the shaft rapidly upward upon release of the latch whereby said wheel is moved along the grooves into biting engagement with the inner periphery of the casing, said wheel in engaged position adapted to be rotated along the grooves in response to downward movement of the body portion for moving the cutter into contact with the casing.
